CLAIM

I claim the ornamental design of a cut stone, as shown and described.

DESCRIPTION

FIG. 1 is a front, perspective view of a first embodiment of a cut stone showing a twelve sided chaton rose having a girdle at the base of my new design;

FIG. 2 is a front, elevational view of the first embodiment of the cut stone of FIG. 1, the rear side elevational view being the same;

FIG. 3 is a top plan view of the cut stone of FIG. 1, the bottom being flat and unornamented;

FIG. 4 is a front, perspective view of a second embodiment of a cut stone showing a sixteen sided chaton rose having a girdle at the base of my new design;

FIG. 5 is a front, elevational view of the second embodiment of the cut stone of FIG. 4, the rear side elevational view being the same; and,

FIG. 6 is a top plan view of the cut stone of FIG. 4, the bottom being flat and unornamented.
